F. I. DU PONT.
FUEL BURNER FOR STEAM GENERATORS.
APPLICATION FILED MAR. 3, 1917.

UNITED STATES PATENT OFFICE.

FRANCIS I. DU PONT, OF WILMINGTON, DELAWARE.

FUEL-BURNER FOR STEAM-GENERATORS.

1,290,132.

Specification of Letters Patent.

Patented Jan. 7, 1919.

Application filed March 3, 1917. Serial No. 152,190.

To all whom it may concern:

Be it known that I, FRANCIS I. DU PONT, a citizen of the United States, residing at Wilmington, county of New Castle, and State of Delaware, have invented a new and useful Improvement in Fuel-Burners for Steam-Generators, of which the following is a full, clear, and exact description, reference being had to the accompanying drawings, which form a part of this specification.

The object of my invention is to provide improved means for supplying liquid fuel to a steam boiler and which will be particularly adapted to the supplying of liquid fuel to the boiler of a steam driven motor vehicle. More specifically, my object is to utilize steam or compressed air, preferably steam from the boiler under normal working conditions, to both lift the fuel, atomize it and spray it, and at the same time aspirate the required quantity of air into the fire-box, and so arranged that upon the cutting off of the steam the flow of fuel will automatically stop. A further specific object of the invention is to provide means for regulating the pressure of the steam in the boiler.

In the embodiment of my invention herein described I so construct the jet that the pressure required to insure its proper operation will be very much below the maximum pressure desired in the boiler and safely below any unusually low pressure in the boiler arising from any sudden use of steam. Between the boiler and the atomizing jet regulating means are arranged whereby a constant pressure at the atomizing jet, of a degree most favorable to the working of the jet, will be maintained notwithstanding slight variations in boiler pressure, and whereby, when the boiler pressure exceeds a predetermined maximum, the flow of steam from the boiler to the atomizing jet will be shut off, thereby stopping also the supply of fuel.

A further object of the invention is to provide means for securing a steady flow of fluid, under requisite pressure, to the atomizing jet before steam is generated in the boiler.

A preferred embodiment of the invention is shown in the drawings, in which:

Figure 1 is a view in side elevation, partly in section, of the apparatus.

Fig. 2 is a detail view of the atomizing jet.

Fig. 3 is a detail view of one of the pressure regulators.

The steam boiler *a* has within its fire-box a grille work *b* of refractory material to retain and uniformly distribute the heat, and to insure complete combustion of the fuel before the burning gaseous mixture comes in contact with the relatively cool surface of the boiler. The floor of the fire-box slopes downward toward an opening *c* of known form within which projects the front of the fuel injector.

The injector, one of several practicable forms of which is shown in detail in Fig. 2, with the delivery end enlarged for purposes of clearness, comprises a tubular chamber *d* having a slightly outwardly flaring opening, and a steam pipe *e* extending longitudinally through the chamber *d* and the somewhat tapered nozzle end of which extends partly within the mouth of the chamber *d*.

Somewhat below the fuel injector *d* *e* is a receptacle *f* containing liquid fuel, such as kerosene or gasoline, having an inlet pipe *g* communicating with its bottom. Within the receptacle *f* is a float *h* to which is secured the stem of a valve *i* which, when the float is at a predetermined level, shuts off the admission of liquid fuel. A pipe *j* connects the receptacle with the tube *d*.

It is important that the level of fuel in the receptacle *f* shall be maintained a sufficiently short height *x* below the level of the fuel injector and that the latter shall operate to aspirate the required quantity of air into the fire-box. This is particularly true of steam driven road vehicles, for which use my invention is more particularly adapted, because the use of a smokestack, which would perform the desired function in an ordinary furnace, is inadmissible in an automobile. In the particular form of jet shown in detail in Fig. 2, the tendency to expand of the steam jet in the conical opening of the tube *d* produces a sufficient vacuum to lift the liquid fuel. This type of atomizing aspirating jet is not new *per se*, and I do not wish to be limited to any particular construction of jet, as other constructions are known and practicable. It will also be understood that the pressure most favorable to the working of the jet will vary with the construction thereof.

In regulating the pressure at the atomizing jet and maintaining it constant and in regulating the pressure of steam in the boiler, I interpose in the steam pipe connections between the boiler and the fuel in-

jector two pressure regulators, which will now be described.

The first regulator *h* nearest the boiler is controlled by the pressure of the steam behind it (that is, in the boiler) and serves to close the steam connections and so stop the fuel spray when the pressure rises above a predetermined maximum, say, for example, 600 pounds to the square inch. This regulator is shown in Fig. 3. It comprises a needle valve *m* located at the junction of two sections of the steam pipe, a diaphragm *n* secured to the stem of the valve, a frame *o* supporting the diaphragm and the valve seat, a steam chamber *p* back of the diaphragm, and an adjustable spring *r* set to resist a definite pressure of steam. A branch pipe *s* connects the pipe *e* (between the boiler and the valve) with the chamber *p*. When the pressure of steam exceeds a predetermined maximum, the valve *m* closes and shuts off the flow of steam to the atomizing jet, and this being done the fuel ceases to be delivered to the fire-box.

The second regulator *t* may be identical in construction with the regulator *h* and is interposed in the pipe *e* between the pressure regulator *h* and the fuel injector. Its steam chamber is connected, by a pipe *u*, with the section of pipe in front of the valve of regulator *t*, so that if the steam pressure effective at the atomizer exceeds a predetermined maximum, say 50 pounds, the valve of regulator *t* will close until the pressure drops.

In order that pressure fluid may be supplied to the atomizer when there is no steam in the boiler, as in starting the engine, I provide an air pump *v* connected, by a valved pipe *w*, with the boiler. The pump is operated until the air within the boiler is compressed to the degree required to insure, after the valve *y* on the pipe *e* is opened, a steady flow of compressed air to the fuel injector until, after ignition of the fuel, a sufficient head of steam is generated to perform the same function.

Having now fully described my invention, what I desire to claim and protect by Letters Patent is:

1. In a fuel burner for steam generators, the combination with the boiler and its fire-box having an opening to admit a spray of liquid fuel, of a steam pipe connected with the boiler, a source of liquid fuel supply, an injector connected with the steam pipe and the fuel supply and adapted, at a proper steam pressure, to inject fuel into the fire-box, and regulating means interposed in the steam pipe to maintain the steam pressure at the injector substantially constant and substantially below the steam pressure in the boiler.

2. In a fuel burner for steam generators, the combination with the boiler and its fire-box having an opening to admit a spray of

liquid fuel, of a steam pipe connected with the boiler, a source of liquid fuel supply, an injector connected with the steam pipe and the fuel supply and adapted, at a proper steam pressure, to inject fuel into the fire-box and to cease to inject fuel when the steam pressure drops, and two regulators interposed in the steam pipe, one adapted to maintain the steam pressure at the injector substantially constant and substantially below the steam pressure in the boiler and the other adapted to shut off the flow of steam, and hence also the supply of fuel, when the pressure of steam in the boiler rises above a predetermined maximum.

3. In a fuel burner for steam generators, the combination with the boiler and its fire-box having an opening to admit a spray of liquid fuel, of a liquid fuel receptacle, a valve controlling the admission of fuel to the receptacle, a float in the receptacle connected with the valve and adapted to regulate the level of liquid fuel in the receptacle, an exit pipe from said receptacle, a steam pipe connected with the boiler, and an atomizing aspirating injector opposite said opening and located above said predetermined level and connected with both pipes, and means interposed in the steam pipe to maintain the steam pressure at the injector substantially constant and substantially below the steam pressure in the boiler and to cut off the flow of steam from the boiler when the pressure in the latter rises above a predetermined maximum.

4. In a fuel burner for steam generators, the combination with the boiler and its fire-box having an opening to admit a spray of liquid fuel, of a fuel supply pipe, a steam pipe connected with the boiler, a fuel injector connected with both pipes, and two pressure regulators interposed in said steam pipe, one adapted to maintain a constant pressure of steam in the injector notwithstanding variations in boiler pressure and the other adapted to cut off the flow of steam from the boiler when the pressure therein rises above a predetermined maximum.

5. In a fuel burner for steam generators, the combination with the boiler and its fire-box having an opening to admit a spray of liquid fuel, of a fuel supply pipe, a steam pipe connected with the boiler, a fuel injector connected with both pipes, and two pressure regulators interposed in said steam pipe, one comprising a valve in the steam pipe and a connection between the pressure face of the valve and the injector, and the other comprising a valve in the steam pipe between the first valve and the boiler and a connection between the pressure face of the second valve and the boiler.

6. In a fuel burner for steam generators, the combination with the boiler and its fire-box having an opening to admit a spray of

- liquid fuel, of a liquid fuel container, means to supply liquid fuel to the container and to regulate the level of the fuel therein, a pipe leading therefrom, a steam pipe connected 5 with the boiler, an atomizing aspirating injector located opposite said opening above the predetermined level of the liquid fuel and connected with both pipes, and two pressure regulators interposed in the steam 10 pipe, one comprising a valve in the steam pipe and a connection between the pressure face of the valve and the injector, and the other comprising a valve in the steam pipe between the first valve and the boiler and a 15 connection between the pressure face of the second valve and the boiler.
7. In a fuel burner for steam generators, the combination with the boiler and its firebox having an opening to admit a spray of 20 liquid fuel, of a liquid fuel receptacle, a valve controlling the admission of fuel to the receptacle, a float in the receptacle connected with the valve and adapted to regulate the level of liquid fuel in the receptacle, an exit pipe from said receptacle, a steam 25 pipe connected with the boiler, an atomizing aspirating injector opposite said opening and located above said predetermined level and connected with both pipes, and two pressure regulators interposed in the steam 30 pipe, one adapted to maintain a constant pressure of steam in the injector notwithstanding variations in boiler pressure below a predetermined maximum and the other adapted to cut off the flow of steam from the 35 boiler when the pressure therein arises above a predetermined maximum.
- In testimony of which invention I have hereunto set my hand, at Wilmington, Delaware, on this 28th day of February, 1917. 40

FRANCIS I. DU PONT.
